UNITED STATES PATENT OFFICE.

CHARLES J. GRAYSON, OF HUNTINGTON, WEST VIRGINIA, ASSIGNOR TO THE ARM-
STRONG ELECTRIC AND MANUFACTURING CORPORATION, OF HUNTINGTON, WEST
VIRGINIA, A CORPORATION OF DELAWARE.

DESIGN FOR A COMBINED PERCOLATOR AND TOASTER.

Application filed September 6, 1928. Serial No. 28,056. Term of patent 14 years.

To all whom it may concern:

Be it known that I, CHARLES J. GRAYSON, a citizen of the United States, residing at Huntington, in the county of Cabell and State of West Virginia, have invented a new, original, and ornamental Design for Combined Percolator and Toaster, of which the following is a specification, reference being had to the accompanying drawing, forming part thereof.

The figure is a perspective view of the combined percolator and toaster showing my new design.

I claim:

The ornamental design for a combined percolator and toaster, as shown.

CHARLES J. GRAYSON.
